UNITED STATES PATENT OFFICE.

VICTOR ANGERER, OF PHILADELPHIA, PENNSYLVANIA, ASSIGNOR TO
WILLIAM WHARTON, JR., AND COMPANY, INCORPORATED, OF SAME
PLACE.

STREET-RAILWAY CROSSING.

SPECIFICATION forming part of Letters Patent No. 449,433, dated March 31, 1891.

Application filed January 5, 1891. Serial No. 376,749. (No model.)

To all whom it may concern:

Be it known that I, VICTOR ANGERER, a citizen of the United States, and a resident of Philadelphia, Pennsylvania, have invented
5 certain Improvements in Street - Railway Crossings, of which the following is a specification.

The object of my invention is to form a rigid and simply-constructed railway-crossing especially applicable for street-railways using the type of rail known as a "girder" rail. This object I attain in the following manner, reference being had to the accompanying drawings, in which—

15 Figure 1 is a plan view, partly in section, of my improved railway-crossing. Fig. 2 is a plan view of one corner of the crossing drawn to a larger scale. Fig. 3 is a sectional view on the line 1 2, Fig. 2. Fig. 4 is a view looking in the direction of the arrow, Fig. 2, showing the crossing-rails, but the main rail removed. Fig. 5 is a diagram view illustrating the manner of bringing up crossing-rails to the main rails to form the joint. Fig. 6 is a 25 perspective view illustrating the cut-out main rail, and Fig. 7 is a perspective view showing the ends of the crossing-rails cut to fit the main rail.

Heretofore in constructing street-railway crossings reliance has been placed upon the securing-bolts to hold the several parts together, these bolts taking the vertical and horizontal strain, and it is to overcome this objection to the present style of crossing that 35 my invention has been designed.

A are the main rails, which are unbroken as regards the web, base, and flange, and B B are the sectional crossing-rails, formed in the present instance in three sections b b' b², the 40 section b being between the main rails, and the sections b' b² being on the outside of the main track, as shown in Fig. 1. The head and wagon tread or flange of the main rail is, as shown in Fig. 6, notched at a a', and in 45 some instances the base-flange is also notched in the same manner as the head and wagon-tread. The end of the rail-section b of the crossing-rail is shaped, as shown in Fig. 7 and also in Fig. 4, to fit the notched portion a' of 50 the main rail as well as to follow the contour

of the body portion of the rail. The ends of the sections b' and b² are likewise shaped to fit the notches a and the outside contour of the main-track rails.

D D are right-angled brackets, which secure the crossing-rails to the main rails, bolts d passing through one arm of the bracket, through the web of the main rail and through an arm of an opposite bracket, while bolts d' secure the brackets to the crossing-rails. Thus 55 on referring to Fig. 1 it will be seen that after the several parts are fitted the brackets are secured to the crossing-rails, and by drawing said crossing-rails into position by the bolts d, as shown in Fig. 5, a tight joint is 60 formed between the main rails and crossing-rails, as shown in Fig. 2. It will be noticed that one side of each notch is at an angle for the purpose of drawing the crossing-rail sections into the recesses or notches, thus insuring a tight fit. The vertical and side strains 65 are thus taken up by the rails themselves, rather than by the securing-bolts, the latter being subjected only to the ordinary tensile strain.

75 At the inside corners of the crossing are angular plates e, secured to the wagon - tread flange by riveted bolts, these plates being tapered, as shown in Fig. 4. Tapered plates f are also secured to the wagon-tread flanges on 80 the outside of the joints in the same manner as the plates e. These corner-plates are merely filling-plates to allow the wagon-wheel to pass over the heads of the rails. They also help to strengthen the rails at the joints, but are 85 not essential for this purpose.

I claim as my invention—

1. The combination, in a street - railway crossing, of sectional cross-rails, an unbroken main rail notched for the reception of the ends 90 of the cross-rails, and means for securing the cross-rails to the main rail, substantially as set forth.

2. The combination, in a street - railway crossing, of the unbroken main rail, notched 95 substantially as described, the sectional cross-rails, the ends of which are so formed as to fit said notches, and angular brackets secured to the main rail and crossing-rails, substantially as set forth.

3. The combination of the main rail having a tapering notch, a section of a crossing-rail adapted to said tapered notch, and means for securing the crossing-rail to the main rail, substantially as described.

4. The combination of the notched main rail, the sectional crossing-rail having ends adapted to the notches in the main rail, means for securing said rails together, and an angular wagon-tread plate at the junction of the

rails and secured to both the main and cross rails, substantially as set forth.

In testimony whereof I have signed my name to this specification in the presence of two subscribing witnesses.

VICTOR ANGERER.
